SLIP-INDEX FOLDER

George W. Shaw, Muskegon, Mich., assignor to
 The Shaw-Walker Company, Muskegon, Mich.,
 a corporation of Michigan

Application October 29, 1938, Serial No. 237,671

8 Claims. (Cl. 129—15)

This invention relates to a slip-index folder, and consists of the matters hereinafter described and more particularly pointed out in the appended claims.

5 The object of the invention is to provide a slip-index folder adapted to be made from a single blank which comprises back sections and an interposed plurality of narrow index guides between which the slips may be inserted as desired, said index guides maintaining the slips as if in separate compartments.

Another object of the invention is to produce a slip-index folder which is of economical construction and which may be manufactured at 15 small cost.

The advantages of the invention will appear more fully as I proceed with my specification.

In the drawings:

Figure 1 is a view showing the improved slip-index folder as it appears with slips therein and partially open.

Figure 2 is a view representing the folder containing the slips opened out flat on its back.

Figure 3 is a perspective view showing the 25 folder with slips therein, and particularly the back expanded edge of said folder.

Figure 4 is a view showing a section through the folder filled with slips, in a plane indicated by the line 4—4 of Figure 1.

30 Figure 5 is a plan view of a blank made of a sheet of heavy paper or light cardboard, cut and scored to form the folder.

Figure 6 is a perspective view showing the blank partially folded.

35 Figure 7 is a perspective view of the blank more closely folded with the index-dividing members spread out fanwise to show how they divide the space within the folder to receive the slips the folder is to contain.

40 Referring now to that embodiment of the invention illustrated in the drawings: 10 in Figure 5 indicates the blank for forming the folder. It is made of a sheet of comparatively stiff paper or light cardboard and is of horizontally elongated rectangular form. It is cut to provide like front and rear rectangular vertical back sections 11 and 12. Each back section has a laterally projecting tab 11^a, 12^a, respectively,—the tab 11^a being located at the top of the front back 11, and the tab 12^a being located at the bottom of the rear back 12. 11^b and 12^b indicate fold lines, respectively defining the inner edges of the back sections 11 and 12.

55 Intermediate the fold lines 11^b and 12^b is a

section 13, twice the width of the back sections 11 and 12 in the zone of their tabs. Said section 13 is cut and formed to provide narrow index guide members for the folder. It is divided midway of its width by a vertical fold line 14 into 5 equal parts 13^a, 13^a. Said parts are identical and are as wide as the front and back sections of the folder in the neighborhood of their index tabs. The section 13 is notched out at the top and bottom to points 15 and 16, respectively, on the fold line 14, which are substantially in horizontal alignment with the bottom and top, respectively, of the tabs 11^a and 12^a.

The section 13 of the blank is cut or slit through on horizontal parallel vertically spaced 15 lines 17 crossing the fold line 14 at equally spaced points on that line, and extending to the fold lines 11^b, 12^b. In this case nine of such spaces

are used, thus dividing the section 13 into nine 20 separate parts, each foldable upon itself about the line 14. 19 indicates notches above the slits or cuts 17 extending laterally from the fold lines 11^b, 12^b. Above and below said series of notches the fold lines 11^b, 12^b are scored.

To bring the blank into folder form, the back 25 sections 11 and 12 are folded along the lines 11^b and 12^b towards each other, and the intermediate section 13 is folded on the line 14 in the reverse direction, as shown in Figure 6. The folding is continued until the back sections are brought together with the parts of the intermediate section 13 in contact with each other and interposed between said back sections. The intermediate section 13 thus folded between the back sections

30 presents a plurality of narrow index guide members 13^b which are duplex in form, as shown in Figures 1 and 2. They may be fanned out as shown in Figure 7, and separated when required to insert slips between them into the folder. The notches 19 provide greater freedom of movement between the index guide members when swinging them apart to define associated pockets in the folder. The guide members are provided at their outer ends with index characters of any kind desired, as for example numerals in this case. In order to accommodate the expansion of the folder with the insertion of slips between the index guide members, the back sections 11 and 12 are provided with score lines at an angle 35 40 to the fold lines 11^b, 12^b, the one diverging slightly from the top to the bottom as indicated at 11^c, and the other diverging to the same extent from the bottom towards the top as indicated at 12^c.

45 On account of this construction, the folder 50 55 55

when filled will assume on its rear edge the shape indicated in Figure 3, with the fold lines 11^b, 12^b following a diagonal line from the bottom end of the score line 12^c to the top end of the 5 score line 11^c, as shown in Figure 3.

The manner of use of the improved slip-index folder will be obvious from the foregoing description and from an examination of Figures 1 and 2. The index guides extend beyond the 10 edges of the back sections of the folder where they are exposed as index tabs offset from top to bottom in line with the tabs 11^b, 12^b of said back sections. The desired index tab is thus readily grasped for opening the folder to insert 15 (or remove) a slip or slips in proper relation to an index guide. And said index guides will maintain the slips in the folder in the classified, separated relation denoted by the index characters on the exposed tabs of the index guides, 20 as shown in Figure 1.

I claim as my invention:

1. A slip-index folder formed from a single blank cut and scored to provide laterally spaced back sections and an intermediate section foldable upon each back section and foldable midway between said backs upon itself, said intermediate section being slit upon a plurality of horizontally spaced lines to provide narrow duplex index guides independently hinged between said back 30 sections.

2. A slip-index folder formed from a single blank cut and scored to provide laterally spaced back sections each having a laterally projecting tab, one being at the top and the other being 35 at the bottom of the blank, and an intermediate section equal in width to the combined width of said back sections in the zone of said tabs, said intermediate section being foldable upon each back section, being foldable midway between said 40 backs upon itself, and being slit along a plurality of horizontally spaced lines to provide narrow duplex index guides independently hinged between said back sections.

3. A slip-index folder formed from a single blank cut and scored to provide laterally spaced back sections and an intermediate section foldable on each back section and foldable midway between said back sections upon itself, said intermediate section being slit upon a plurality of 50 horizontally spaced lines to provide narrow duplex index guides independently hinged between said back sections, said index guides being provided with elongated notches above said slits extending from the line of fold between said back 55 and intermediate sections.

4. A slip-index folder formed from a single blank cut and scored to provide laterally spaced back sections and an intermediate section foldable upon each back section and foldable midway 60 between said back sections upon itself, said blank being provided with diverging lines of weaken-

ing adjacent the fold lines between said sections, the divergence in one case being towards the top of the blank and in the other being towards the bottom of the blank, said intermediate section being slit upon a plurality of horizontally spaced 5 lines to provide narrow duplex index guides independently hinged between said back sections.

5. A slip-index folder formed from a single blank cut and scored to provide laterally spaced back sections and an intermediate section foldable upon each back section and foldable midway between said back sections upon itself, said blank being provided with diverging lines of weakening adjacent the fold lines between said sections, the divergence in one case being towards the top of the blank and in the other being towards the bottom of the blank, said intermediate section being slit upon a plurality of horizontally spaced 10 lines to provide narrow duplex index guides hinged between said back sections, 15 and being provided with elongated notches above said slits extending laterally from the fold lines between said sections.

6. A slip-index folder formed from a single blank cut and scored to provide laterally spaced 25 back sections, each having a laterally projecting tab, one being at the top and the other being at the bottom of the blank, and an intermediate section equal in width to the combined width of said back sections in the zone of said tabs, 30 said intermediate section being foldable upon each back section and being foldable midway between said back sections upon itself, the top and bottom edges of said intermediate section before folding, each being in the form of an obtuse 35 angle with its apex in the median fold line of said section and in horizontal alignment with the top and bottom, respectively, of the tabs on said back sections, and said intermediate section being slit along a plurality of horizontally spaced lines 40 to provide narrow duplex index guides independently hinged to said back sections.

7. A slip-index folder comprising back sections and a plurality of narrow, horizontally elongated duplex index guides, each part of each guide 45 being independently hinged to an associated back section, and said index guides projecting beyond the free edges of said back sections to present tabs for index characters.

8. A slip-index folder comprising back sections 50 hinged together, one back section having a laterally extending tab at the top, and the other having a laterally extending tab at the bottom, and a plurality of horizontally elongated duplex index guides located between said sections, each 55 part of each guide being independently hinged to an associated back section, and said index guides projecting beyond the free edges of said back sections to present tabs for index characters offset in line with the tabs on said back sections. 60

GEORGE W. SHAW.
